UNITED STATES PATENT OFFICE.

HENRY E. PARSON, OF NEW YORK, N. Y.

AIR AND STEAM INJECTOR FOR FURNACES.

SPECIFICATION forming part of Letters Patent No. 241,710, dated May 17, 1881.

Application filed September 14, 1880. (No model.)

To all whom it may concern:

Be it known that I, HENRY E. PARSON, of the city, county, and State of New York, have invented certain new and useful Improvements 5 in Air and Steam Injectors for Furnaces, of which the following is a specification.

This invention relates to improvements in the hydrocarbon-injector for which Letters Patents have been granted to me under date of June 10 5, 1877, and numbered 191,546, by which the same is simplified in construction and adapted to throw a mixture of steam and air into the furnace of a steam-boiler for the purpose of aiding in the combustion of the fuel and increasing 15 the amount of heat to be obtained therefrom.

The invention consists of an annular steam-chamber which is connected by a pipe to the steam-boiler, and provided at one end with a cylindrical nozzle, which is adjusted by a hand-wheel 20 in a guide-cylinder of the steam-chamber. To the opposite end of the steam-chamber is applied an air-tube, the tapering inner end of which forms, in connection with the correspondingly tapering inner end of the nozzle, a narrow 25 annular discharge-orifice for the steam, which, in being forced through the nozzle, draws in the air through the air-tube and forces it through an exterior casing and conducting-trunk into the furnace.

30 The accompanying drawing represents a vertical longitudinal section of my improved air and steam injector for furnaces of all kinds.

A in the drawing represents the exterior casing of my improved air and steam injector, 35 which casing is connected by a trunk, B, with the ash-pit of a steam-boiler or other furnace, opening below the grate of the same.

At the inside of the casing A is arranged the injector C, the annular steam-chamber D of 40 which is connected by a pipe, D', to a steam-boiler. The annular steam-chamber D is provided at one end with a cylindrical extension, D², within which is guided a cylindrical nozzle, E, a steam-tight connection between the 45 guide-cylinder and nozzle being obtained by a packing-nut, D³. The nozzle E has an exterior screw-thread at its inner end, by which and a hand-wheel, E', at its outer end it may be screwed into or out of the guide-cylinder D², which has a corresponding interior thread. The hand-wheel E' is readily taken hold of for adjusting the nozzle E by opening a hinged

door, a, of the casing A. The contact-surface of the guide-cylinder D² of the steam-chamber and nozzle E is lubricated by an oil-cup, d, by 55 which the motion of the guide-cylinder during adjustment is facilitated. The guide-cylinder D² is further provided with a small petcock, e, for discharging the condensed steam. To the opposite end of the annular steam-chamber 60 D is applied an air-tube, F, which is preferably made of cone or funnel shape and provided at its inner edge with an exterior conically-tapering seat, f, which is accurately fitted into the conical rear end of the nozzle E. 65

Back of the conical seat of the air-tube F is arranged a shoulder, f', against which the inner end of the nozzle abuts when the same is turned back sufficiently.

Between the tapering seat of the air-tube and the conical inner edge of the nozzle is formed a narrow annular orifice or throat, through which the steam is forced on its way from the steam-chamber into the nozzle. The amount of steam passing through the nozzle is controlled by enlarging or contracting the escape orifice or throat by the adjustment of the nozzle in its guide-cylinder. The steam escapes in the shape of a cone into the nozzle, and creates thereby a partial vacuum, which draws in 70 the air through the air-tube, causing the same to rush forward and become heated and expanded by the steam. The body of steam, issuing through the discharge-orifice of the nozzle, exerts also a suction upon the air surrounding 75 the injector in the casing A, which air mingles with the steam and the air drawn in through the air-tube, being conducted by the trunk B to the ash-pit and into the fire, where the steam is decomposed into hydrogen and oxygen and 80 burned, together with the air thrown in by the injector. A more perfect combustion and utilization of the fuel is thereby secured and an increased amount of heat generated, so that a 85 considerable saving in fuel results from the application of the air and steam injector. 90

Having thus described my invention, I claim as new and desire to secure by Letters Patent—

1. In an air and steam injector for furnaces, the combination of an interior injector having 100 an annular steam-chamber, an adjustable nozzle at one end and a fixed air-tube at the opposite end of the steam-chamber, with an inclosing-casing, which is open at one end and pro-

vided with a conducting-trunk at the opposite end, in front of the nozzle of the injector, substantially as set forth.

2. A steam and air injector for furnaces, consisting of an annular steam-chamber, of an adjustable cylindrical nozzle at one end, and of an air-supply tube at the other end, the air-tube extending through the steam-chamber and into the rear part of the nozzle, substantially as set forth.

3. In an air and steam injector for furnaces, the combination of an annular steam-chamber having a guide-cylinder and packing-nut at one end and a fixed air-tube at the other end with 15 an adjustable cylindrical nozzle, which forms, with the air-tube, a narrow annular orifice or throat, substantially as described.

4. In an air and steam injector for furnaces, the combination of an annular steam-chamber having a guide-cylinder and packing-nut with 20 an adjustable cylindrical nozzle at one end and a fixed air-tube at the other end of the steam-chamber, the adjoining inner ends of the nozzle and air-tube being made tapering, so as to form a narrow annular issuing orifice or throat, 25 substantially as described.

In testimony that I claim the foregoing as my invention I have signed my name, in presence of two witnesses, this 11th day of September, 1880.

HENRY E. PARSON.
